REINFORCED FIBROUS LAYER

Frank L. Bryant, East Orange, and Gustave S. Mathey, Elizabeth, N. J., assignors to Cellufoam Corporation, Chicago, Ill., a corporation of Delaware

Application November 11, 1933, Serial No. 697,628

1 Claim. (Cl. 92—40)

The present invention is directed to a reenforcement of layers of fibrous material of the character set forth and described in the Bryant Patent No. 1,740,280, issued December 17, 1929, although the material may be modified to include certain features described in the Bryant Patent No. 1,841,785, issued January 19, 1932, as well as certain features described in the Bryant application Serial No. 599,329, filed March 16, 1932 and sued as Patent No. 1,966,437, dated July 17, 1934.

The fibrous material which furnishes the basis for the layer of the present invention is preferably formed of cellulose fibers, which are first mixed with a large percentage of water to which is added a quantity of saponin or similar foam forming ingredient, after which the mix is agitated to cause foaming and distension of the fibers, and in this condition is flowed upon the foraminous bed of a Fourdrinier machine in the form of a relatively thick layer which is fed forward in an uncomplicated state and partially drained and afterwards dried under conditions which preserve the layer in its fluffy or distended condition. If desired, waterproofing or fireproofing ingredients may be added to the mix, and the advancing layer may be subjected to vacuum while being carried forward on the Fourdrinier machine in such manner as to form a relatively tough coherent skin on the surface of the layer, and furthermore, if desired, relatively long hair-like fibers may be incorporated into the mix for the purpose of binding the layer more firmly together.

The nature of the layer, and the various methods of modifying its character, texture and qualities, are described in full detail in the patents above mentioned, and in the process and product of the present invention it will be understood that it is the intention to utilize a layer of the general character indicated in the original Bryant Patent No. 1,740,280, which may if desired be modified in one or more of the ways indicated in the remaining Bryant patents.

The present invention is directed to the incorporation into the layer itself of a gauze or similar fabric, which unites with the layer in such a way as to strengthen and reinforce the layer and afford increased tensile strength which is not present in substantial degree in the felted layer formed in the manner set forth in the above named patents and application. The gauze or other fabric is applied to the layer during the formation thereof in such a way as to cause the cellulose fibers of the layers to intermesh with the fabric and become interspersed into the inter-

stices thereof so that the fabric is to some extent incorporated into the texture of the layer either by being bodily imbedded within the interior of the layer or applied to the surface thereof while the layer is in the formative stage, so that a close intermeshing of the fibers occurs.

The fabric may be applied to the surface of the layer while the mix is being flowed onto the bed of the Fourdrinier machine, and at a time when the mix contains a very large percentage of water, so that during the draining and drying operation the fabric will become intermeshed or entangled with the surface fibers of the layer in such a manner as to cause adherence of the fabric to the surface, or if desired the fabric can be spread upon the surface of an under layer of the mix while being flowed upon the bed of the Fourdrinier machine and a second layer deposited from above, in which case the fabric will be completely imbedded within the interior of the completed product by the coalescence of the two layers while in the semi-liquid state and the intermeshing of the fibers through the interstices of the fabric. It will therefore be understood that where reference is made to the intermeshing of the fibers with the texture of the fabric, it is intended to cover either the surface application of the fabric or the complete imbedment thereof, as the case may be, since in either case the intermeshing is one which serves to retain the fabric in place and to afford sufficient adhesion to reinforce the texture of the layer in such a way as to prevent rupture under ordinary conditions of use.

The reenforced layer of the present invention is designed particularly for use in surgical dressings, or for antiseptic purposes, or under various conditions of use in which an absorbent layer is desired, although by suitable treatment one or both of the surfaces may be proofed or rendered non-absorbent, or otherwise modified in accordance with the principles particularly set forth in the Bryant Patent No. 1,841,781, and the Bryant application Serial No. 599,329. It will also be understood that although the method of forming the layer as described and illustrated in the Bryant Patent No. 1,841,785 furnishes a convenient and desirable method of forming the mix and flowing it out in layer form and under conditions which readily permit of the application of the gauze or similar reenforcement described in the present invention, it is not the intention to limit the method of applying reenforcement to the layer, since any convenient method may be employed which permits the fabric layer to be inter-

meshed with or completely imbedded within the body of the fibrous layer while still in the formative stage and under conditions which provide for the interspersion or intermeshing of the fibers with the texture of the fabric in such a way as to unite the one to the other.

In order to better define the nature of the present invention, reference is had to the accompanying drawings, wherein.

10 Figure 1 is a perspective view of a section of the material showing the gauze reenforcement applied to the surface thereof;

15 Fig. 2 is a perspective view showing the fabric imbedded within the interior, and the surface layer partly broken away to better expose the fabric;

20 Fig. 3 is an enlarged sectional detail showing the manner in which the fibers of the layer are interspersed through the interstices in the fabric reenforcement;

25 Figs. 4, 5 and 6 are longitudinal sectional views of successive portions of one and the same machine designed to continuously produce layers of reinforced distended material; and

30 Fig. 7 is a detail showing a modification designed to discharge the material in upper and lower layers to imbed the reenforcement within the body of the material.

35 The product of the present invention consists of a layer A of distended fibers (preferably of cellulose) which are felted or matted in a loose fluffy condition and reenforced by a fabric B of gauze or the like, which is either applied to the surface as shown in Fig. 1, or imbedded within the interior as shown in Fig. 2. Furthermore, if desired, one or more of the exterior surfaces of the layer may be more densely compacted to afford a paperlike surface skin C which serves to toughen the surface in cases where such a texture 40 is desired.

45 As illustrative of a suitable method of practicing the present invention, the following description is given:

50 Cellulose fibers are introduced into a regular paper stock beater of the Holland, Niagara, or Jordan type, with sufficient water to give the proper consistency to the mix about three percent (3%), and subjected to the action of the beater for a sufficient length of time to produce the desired degree of hydration. This period 55 may be varied, depending upon the condition of the raw fibers and upon the extent to which it is desired to gelatinize the surfaces of the fibers, but for most purposes treatment of an hour will serve to give to the fibers the desired degree of hydration. Where the action is continued sufficiently to soften the surfaces of the fibers, a gelatinizing effect occurs, which modifies the surface condition of the fibers and their capacity 60 to imbed themselves into one another at the points where they contact or intersect, so that they are thus in a better condition to felt or intermesh together than in cases where a lesser degree of hydration is employed, although it will 65 be understood that the present invention is not primarily concerned with the above details, but where a proper degree of adherence is desirable, such condition is prompted by the gelatinizing of the fiber surfaces.

70 After the fibrous materials have been sufficiently beaten and hydrated, it is necessary to incorporate with the liquid mixture a suitable quantity of bubble forming or foam forming ingredient of the character set forth in the Bryant 75 Patent No. 1,740,280. It may also at this stage

be desirable in certain cases to incorporate with the mass a quantity of hair or other relatively long fibrous material where it is desired to secure a more coherent texture in the completed product, although in the present instance the use of the gauze or similar reenforcing fabric will ordinarily render it unnecessary to provide for additional methods of reenforcement.

5 The foam forming ingredient which is preferred is saponin, which may be added in the proportion of substantially one part of saponin to four hundred parts of water in the mixture, and after the addition of saponin or other bubble forming ingredients, the mixture, either with or without the addition of proofing agents, is 15 subjected to agitation in the manner set forth in the Bryant Patent No. 1,740,280 for a sufficient period of time to cause the mass to distend and assume a foamy condition through the action of the bubble forming or foam forming ingredients, and until the mass has expanded to about two and a half times its original liquid volume.

20 Where it is desired to waterproof or fireproof the layer, various ingredients of the character particularly described in the Bryant application Serial No. 599,329 may be added to the mix and incorporated with the fibers, either before or during the agitating operation.

25 As an example of an adequate waterproofing method, the following description is given:

30 Take substantially 150 parts by weight of air dried fibers, 4700 parts of water, 10 parts of the foam forming ingredient saponin, and 6 to 9 parts of wax which has been precipitated by 35 acid or an acid salt before mixing with the other ingredients. Whip the whole to form a stable foam with the fibers and wax dispersed throughout the mass, form the mass into the desired shape, remove the excess solution, and dry the 40 formed mass of fibers at temperatures sufficient to cause a fluxing of the minute wax particles onto the fibers to form a waterproof coating or covering for each fiber. In the above process it will be noted that the foaming and waterproofing 45 steps are concurrently performed in a single operation, which is desirable from the standpoint of economy in cases where other considerations do not indicate the necessity for performing the steps separately.

50 As an example of a fireproofing operation, which we prefer in certain cases, we take a slurry of fibers with water to which is added a foam forming ingredient such as saponin, together with 55 15 parts of borax, 6.5 parts of boric acid based on the weight of water used, the whole being whipped to form a stable foam with the fibers incorporated therein, and afterwards formed to shape and dried in the manner previously described.

60 Other methods of proofing or modifying the fibers for the purpose of adding special qualities to the product are in contemplation, but it will be understood that the present invention is directed mainly to the use of a gauze or similar fabric for purposes of reenforcement, and that the special characteristics of the fibers themselves may in each case be modified with a view of imparting to them the desired qualities, which will depend in large measure upon the use for which 70 the reinforced layer is intended.

75 Where the layer is intended for an absorbent bandage, it will, of course, be inadvisable to use any ingredients which will in any way impair its absorbent properties, although in some cases it 75

may be desirable to impart a waterproofing treatment to the mix applied to one side of the reenforcement while maintaining the absorbent properties in the mix intended for application on the other side of the reenforcement. This will result in a bandage or the like which possesses full absorbent properties on one side only, with water repellent properties on the opposite side.

The method of flowing the mix in the form of a layer onto the surface of a Fourdrinier machine, and of subsequently drying the layer while still in uncompressed or distended condition, is fully set forth in the Bryant Patent No. 1,841,785, and it is not deemed necessary to describe the process and mechanism in detail. However, a brief description of the process and mechanism, slightly modified to provide for the feeding of the gauze or other reenforcing agent, will be given, with special reference to the illustrations in Figs. 4 to 7 of the drawings.

After the bubble forming ingredients have been added to the mass, with or without the addition of modifying agents, the mass is poured into a tank 10, within which the material is agitated and distended by the action of propeller blades 11-11 mounted upon a vertical shaft 12, which is driven from a motor 13 or other source of power.

The shaft 12 is preferably located off center with respect to the tank 10, which is preferably circular, so that as the material is driven outwardly by the action of the propeller blades it will sweep around the wall of the tank and be alternately directed inwardly toward the propeller blades and outwardly and away therefrom during its circuit around the tank. While the tank as shown is of cylindrical or circular formation, similar results may be obtained by the use of a barrel shaped tank or one otherwise configured.

The blades of the propeller are preferably formed with downwardly turned tips 14, while the body of each blade is turned upwardly, with the result that when rotating, the blades will have the effect of imparting a combined downward and outward thrust to the material, which gives a vortical motion, and which, combined with the surging action caused by the eccentric relation of the blades to the tank, serves to thoroughly agitate the material without any tendency to additionally break up the minute fibers.

After the material has been thus agitated for a sufficient period to cause it to distend through the action of the bubble forming or foam forming ingredients to about two and a half times its original liquid volume, and after the hair or other material, if any, has been added and has become thoroughly impregnated with and distributed evenly throughout the mass, and while the material is in a creamy state due to the presence of the minute bubbles formed therein, it is discharged in the form of a layer from a spout 15 located near the bottom of the tank, and onto the traveling or foraminous bed or carrier 16 of a Fourdrinier machine.

The bed is preferably formed of fine mesh wire screening and is carried upon supporting rollers 17 and passes around a front idle roller 18 and a rear power driven roller 19. Immediately in advance of the power driven roller, the belt or carrier passes downwardly over a supporting roller 20, and the lower turn of the belt or carrier passes over a rear roller 21, a forward guide roller 22, and under a tension roller 23.

Near the forward end of the Fourdrinier ma-

chine there may be located what may be termed a heavy suction box 24 connected by a suction pipe 25 with a suitable source of vacuum adapted to maintain a relatively heavy vacuum of approximately five inches in the heavy suction box, the purpose of which is to momentarily subject the layer of material, immediately after its delivery onto the bed of the Fourdrinier machine, to a sufficiently heavy suction to draw down and compact the under surface of the layer of material, thereby causing the fibers to cohere and compact together in the formation of a tough paper-like surface skin, where such a skin is desired in the completed product.

Near the rear end of the Fourdrinier machine 15 are located a series of relatively light suction boxes 26 connected by pipes 27 with a suitable source of vacuum 28 adapted to maintain a light suction of approximately three inches of vacuum in the suction boxes, which is a much less degree of vacuum than is commonly employed in the paper making art, and less than the vacuum in the vacuum box 24, the light vacuum boxes being relied upon to withdraw moisture, without, however, additionally compacting the body of 25 the layer of material.

In order to give proper definition to the width of the layer, gauge belts 29 of rubber or suitable composition are employed, one on each side of the bed or carrier, and these belts are properly held and supported to rest upon and travel with the carrier and constitute side walls or flanges for gauging the depth of the layer of material and for affording a sharp or clean cut edge to the layer.

In order to secure a proper depth of material, which should ordinarily be flush with the lower turns of the gauge belts, a scraper bar 30 is provided immediately to the rear of the spout 15, which serves to level down the layer to the level of the gauge belts, after which the layer is not again subjected to any compressive or deformative action save and except the suction previously described.

The gauge belts are mounted upon grooved rollers 31 at the forward and rear ends thereof, and the upper turn of each belt is supported by an intermediate roller 32, which allows the lower turn of each belt to rest bodily upon the moving carrier of the Fourdrinier machine and to travel therewith by friction without the necessity of providing means for positively feeding the gauge belts.

In order to apply the reenforcing gauze or the like to the surface of the wet distended layer of material, the gauze or other reenforcing material is preferably fed from a roll 33 in position to contact the surface of the distended layer and travel therewith during the draining and drying of the layer, so that the gauze will become enmeshed within the fibers of the layer and be held and united thereto in such a way as to secure sufficient coherence to subserve the purposes of the present invention. Where it is desired, however, to completely imbed the gauze or other re-enforcing fabric within the body of the layer, it is desirable to modify the construction sufficiently to provide for the feeding of two layers of the mix and to feed the reenforcing material between the layers so that the upper layer will be flowed over the fabric. In such case, in addition to the lower spout 15, an upper spout 34 is provided, and the gauze or other fabric is fed from above and over a diagonally disposed roller 35 located between the spouts, so that the fabric 75

will be imbedded as the material is discharged from the upper and lower spouts, and the material itself, being in the form of a wet mix, will coalesce through the meshes of the gauze or other reenforcement, thereby serving to hold the re-enforcement permanently in place.

- The reenforced layer of material A passes from the traveling conveyor of the Fourdrinier machine over a stationary shoe 36 and onto the surface of an endless carrier belt 37, the upper turn of which lies flush with the surfaces of the carrier 16 and the shoe 36. The carrier belt 37 is carried upon supporting rollers 38 and passes under a forward roller 39 suitably spaced to dis-
10 tend the forward end of the belt and thereby cause the lower turn to move upwardly in oblique relation to the forward roller 38, as indicated in Fig. 5. The carrier belt 37 passes a rear power driven roller 40, and the upper and lower turns
15 in proximity to the power driven roller are supported on guide rollers 41 and 42, respectively. The upper and lower turns of the endless carrier 37 pass through an elongated drying chamber 43 of boxlike formation, which as shown is supplied with heated air through forward, intermediate and rear ports 44, 45 and 46, respectively. The first port is located near the forward end of the drying chamber, while the last port occupies a position near the discharge end thereof.
20
25
30 Each of the ports, as shown in the figures, is in duplicate, and discharges from each side into the drying chamber at a level with the carrier therein, so that the hot air will be discharged above and below the layer of material being dried, and the duplicate ports in each instance communicate with side ducts 47 which pass upwardly around opposite sides of the drying chamber and receive the heated air from an air delivery duct 48. Similar delivery ducts 49 and 50 deliver the heated air to the intermediate and rear discharge ports 45 and 46, respectively.
35
40

The hot air ducts receive heated air from a furnace or other suitable source of supply, and it is preferred that the hot air delivered to the

forward discharge ports 44 be at a higher temperature than that delivered to the intermediate and rear discharge ports, since in the wetter condition in which the material enters the drying chamber it will stand a higher drying temperature than is desirable at subsequent stages in its progression toward the point of delivery. The air is withdrawn from the bottom of the drying chamber through return ducts 51, 52 and 53, which communicate with an exhaust fan, not shown, for the purpose of maintaining a circuit flow of heated air through the drying chamber.

The product of the present invention is adapted for numerous uses and may be made in various thicknesses, and the texture and quality of the product may be varied in numerous ways. As before stated, the product may be waterproofed on one or both sides, and the formation of a surface skin of the desired toughness or coherence may be included or omitted as desired.

Although the invention is designed particularly with reference to the formation of bandages for surgical or hygienic use, the same general process suitably varied may be employed in the production of layers intended for widely divergent uses. Thus greater or less suction may be applied to the surfaces of the layer to produce a surface skin which will increase the coherence of the layer, and similarly, by the use of such long fibered ingredients as hair or the like, additional toughness and coherence may be added, without, however, destroying the distended condition of the body of the layer due to the foaming of the materials and the flowing and drying of the materials in an uncompressed and undisturbed condition.

We claim:

As a new article of manufacture, a gauze sheet, absorbent distended fibrous material attached to one side and moisture resisting distended fibrous material attached to the opposite side.

FRANK L. BRYANT.

GUSTAVE S. MATHEY.
